PRESSURE FLUID MOTOR

John Clark Curtis, Claremont, N. H., assignor to
 Sullivan Machinery Company, a corporation of
 Massachusetts

Application July 8, 1937, Serial No. 152,608

11 Claims. (Cl. 121—19)

This invention relates to pressure fluid motors, and more particularly to improvements in pressure fluid motors of the reciprocating-piston type especially designed for use in hammer rock drills.

An object of this invention is to provide an improved pressure fluid motor. Another object is to provide an improved pressure fluid motor having improved fluid distribution means. Yet another object is to provide an improved pressure fluid motor of the pressure-fluid-actuated, reciprocating-piston type especially designed for use in hammer rock drills whereby a relatively powerful impact blow and increased efficiency are attained. A still further object is to provide an improved pressure fluid motor having an improved fluid distributing valve and associated passage arrangement whereby, not only is the efficiency of the motor greatly increased, but also reduced fluid consumption may be attained. Other uses and advantages of the invention will, however, hereinafter more fully appear.

In the accompanying drawings there is shown for purposes of illustration one form which the invention may assume in practice.

In these drawings—

Fig. 1 is a view in longitudinal vertical section through an illustrative embodiment of the improved pressure fluid motor.

Fig. 2 is a view similar to Fig. 1, showing certain of the moving motor parts in different positions.

Fig. 3 is a rear end elevational view of the fluid distributing valve.

Fig. 4 is a front end elevational view of the fluid distributing valve.

Fig. 5 is a cross sectional view taken substantially on line 5—5 of Fig. 1.

Fig. 6 is a developed longitudinal sectional view taken substantially on line 6—6 of Fig. 5.

Fig. 7 is a side elevational view of the valve seat plate.

Fig. 8 is a side elevational view of the fluid distributing valve.

Fig. 9 is a front end elevational view of the valve block cover.

Fig. 10 is a rear end elevational view of the valve seat plate.

Fig. 11 is an enlarged fragmentary sectional view of the valve, taken on the plane of Fig. 1, showing the valve in its central position.

In this illustrative embodiment, there is shown a pressure fluid motor, generally designated 1, herein of the reciprocating-piston, hammer type,

especially designed for use in hammer rock drills, although it will be evident that various features of the invention may be incorporated in motors of various other types.

The improved pressure fluid motor, as shown in the drawings, specifically comprises a motor cylinder 2 having a bore 3 containing a reciprocating motor piston 4. In this instance, the motor piston is of the hammer type having a piston head 5 fitting the cylinder bore and a forwardly projecting cylindric portion 6, in the form of a striking bar, adapted to deliver impact blows to a working tool operated by the motor. The cylindric bar portion 6 of the piston is guided in a bore 7 formed in a front buffer ring 8, the latter also constituting the front cylinder head. The cylinder is formed with a rearward extension 9 having a bore 10 aligned with and of somewhat larger diameter than the cylinder bore 3; and arranged in the bore 10 and abutting a shoulder 11 at the juncture of the bores, is a valve seat plate 12, the latter also constituting the rear cylinder head. The plate 12 has formed on its rearward face an annular shoulder 13, and inwardly of said shoulder and projecting rearwardly from the body of the plate is an axial, sleeve-like portion 14 formed with an external annular flange 15. Also arranged in the extension bore 10 and abutting the rear face of the plate 12 is a valve block 16 having bores 17 and 18 partially separated by an inwardly directed annular flange 19, the latter having a bore 20 of substantially smaller diameter than the bores 17 and 18. Abutting the rear face of the valve block 16 and also arranged in the extension bore 10 is a valve block cover 21. Arranged within the rearward portion of the extension bore 10 is a ratchet collar 22, while interposed between this collar and the rear face of the cover 21 is a ratchet ring 23. The valve block cover, ratchet ring and collar are maintained against rotative movement in the bore 10 by a key pin 24 seated in registering grooves in the cooperating parts. The cover 21 is fixed to the valve block 16 by means of a dowel pin 25. Engaging the collar 22 is a back head 26 for holding the parts in assembled relation within the extension bore 10, and this back head and the buffer ring 8 are clamped to the opposite ends of the cylinder in any appropriate manner, as by usual side rods 27, 27 (see Fig. 5).

As is usual in motors adapted for use in hammer rock drills, means is provided associated with the motor piston and operated thereby, for

effecting rotary motion of the piston for the well known purpose of rotating the working tool. This tool rotation means comprises, in addition to the ratchet ring 23, a pawl carrier 29 carrying usual spring-pressed pawls engaging the teeth of the ratchet ring 23, and formed integral with this carrier is a rifle bar 30 having spiral grooves slidingly interlocked with the spiral keys of a rifle nut 31 fixed within the motor piston. The rifle bar at the opposite sides of the pawl carrier 29 is journaled within bores respectively formed in the sleeve-like portion 14 and in the ratchet collar 22, in the manner illustrated. As the motor piston moves forwardly to effect its working stroke, the pawls of the pawl carrier slip over the ratchet teeth so that the forward movement of the piston is unimpeded, and, upon reversal of movement of the motor piston, the pawls of the pawl carrier engage the ratchet teeth to hold the rifle bar against rotation, and, as a result, due to the spiral groove and key interlocking connection of the rifle bar with the piston, the latter is rotated. The rotary motion of the motor piston is transmitted to the working tool in a manner well understood by those skilled in the art. As this tool rotation means as shown is of a conventional form, further description and illustration thereof are unnecessary.

Now referring further to the specific structure of the improved pressure fluid motor, and more particularly to the improved fluid distributing valve mechanism, it will be observed that reciprocably mounted in the valve chamber provided by the cooperation of the parts 12, 16 and 21 is a fluid distributing valve, generally designated 33, having an enlarged external flange 34 near its forward face fitting the front bore 18 of the valve block 16 and a sleeve-like body portion 35 fitting the bore 20 of the internal flange 19 of the valve block. Formed integral with the sleeve-like body portion 35 of the valve is an inwardly directed annular flange 36 having its inner peripheral edge cooperating with the exterior periphery of the flange 15 of the plate body 14, for a purpose to be later explained. Formed in the opposite sides of the valves are internal bores 37 and 38, the latter being of slightly smaller diameter than the former, and being the rearward one of the two. The bore 37 of the valve has, when the valve is in the position shown in Fig. 1, a sliding fit with the shoulder 13 on the plate 12, while the valve bore 38 at the opposite side of the valve flange 36 has, when the valve is in the position shown in Fig. 2, a sliding fit with the exterior peripheral surface 39 of an annular projection 40 formed integral with and projecting forwardly from the forward face of the cover 21. The bores 37 and 38 within the valve at the opposite sides of the internal valve flange 36 are counterbored at 41 and 42 near the opposite end valve faces respectively. The forward face of the external valve flange 34 is annularly recessed at 43 to obtain lightness. Formed in the valve block 16 are ports 44 for connecting the valve block bore 17 with ports 45 formed in the cylinder, and the latter communicate with passages 46 connected by ports 47 with the forward end of the cylinder bore, while an annular recess 48 formed in the rear face of the plate 12 communicates with the front valve block bore 18 at the forward side of the valve, and this recess is connected by passages 49 with the rear end of the cylinder bore. As shown most clearly in Fig. 6, communicating with the front valve block bore 18 at the rear side of the external valve flange

34 is a port 50 in turn communicating with a throwing passage 51 connected at its forward end by a port 52 with the cylinder bore somewhat nearer the rear than to the forward end of the latter. The throwing passage 51 is connected to atmosphere by a restricted leak passage 53. The cylinder bore 3 is annularly grooved at 54 substantially midway between the ends thereof, and this groove is connected to atmosphere through an exhaust port 55.

The means for supplying pressure fluid to the valve chamber comprises a rotary throttle valve 60 arranged in a bore 61 formed in the back head 26, and this valve is formed with an internal pressure chamber 62 connectible by a passage 63 with a passage 64 communicating with a pressure chamber 65 formed within the ratchet collar and back head. This pressure chamber is connected by a series of passages 66 with an annular recess 67 formed in the front face of the ratchet collar, and this recess communicates through the spaces between the ratchet teeth with an annular recess 68 formed in the rear face of the valve block cover 21. The recess 68 is connected by a series of passages 69 with an annular recess 70 in turn connected through a large axial passage 71 extending through the annular projection 40 of the cover, with the valve bore 38 at the rear side of the internal valve flange 36. Pressure may flow from the rear valve bore 38 through the restricted clearance space 72 between the inner peripheral edge of the valve flange 36 and the exterior periphery of the flange 15, to the valve bore 37 at the forward side of the internal valve flange 36. The rear face of the plate 12 is preferably annularly recessed at 73 to increase the volume of the front internal pressure chamber. The distributing valve is guided within the valve chamber exteriorly solely at the outer periphery of the external valve flange 34 and the valve body 35, and the sliding fit which exists in certain relative positions between the uncoversunk portions of the walls surrounding the valve bores 37 and 38, and the exterior peripheries of the annular shoulders 13 and 39 is relatively free, but still an extremely close fluid-tight fit. The inner peripheries of the counterbores cooperate with the exterior peripheries of the annular shoulders 13 and 39 to provide for metering, so that the flow of pressure fluid past the opposite ends of the valve is always the same regardless of any wear of the valve. It will be noted that as the valve moves between its opposite positions, its walls just inwardly of the counterbores 41 and 42 will be momentarily simultaneously in contact with the exterior peripheries of the shoulders 13 and 39 respectively (see Fig. 11), and as a result, waste of pressure fluid due to simultaneous admission to both ends of the cylinder, will be avoided.

The mode of operation of the illustrative form of the improved pressure fluid motor is as follows:

When the throttle valve 60 is in its "on" position shown in Fig. 1, pressure fluid may flow from the interior of the valve through the ports 63, 64, pressure chamber 65, passages 66, annular recess 67, through the spaces between the ratchet teeth, annular recess 68, passages 69, recess 70, and the large axial passage 71, to the bore 38 within the rear end of the valve, and also through the somewhat restricted annular space 72, to the bore 37 at the front of the valve. When the distributing valve is in the position shown in Fig. 1, pressure fluid may flow from the space to the rear of the flange 36 through the metering space between the

wall of the counterbore 42 and the exterior periphery of the annular shoulder 40, past the rear face of the valve portion 35, through the valve block bore 17, and through the ports 44 and 45 and passages 46 and ports 47, to the front end of the cylinder bore. At this time, the rear end of the cylinder bore will be connected to the atmosphere through the exhaust groove 54 and exhaust port 55. Pressure fluid acting on the forward pressure area of the motor piston will move the latter rearwardly to effect its rearward stroke, and when the exhaust groove 54 is closed by the piston head, the fluid trapped in the rear end of the cylinder bore will be compressed by the motor piston. The port 53 will bleed away any fluid which may tend to be compressed within the port 52, passage 51, port 50, and the space to the rear of the flange 34 on the valve. Continued rearward movement of the piston will cause the front edge of the piston head to uncover the forward edge of the exhaust groove 54, connecting the front end of the cylinder bore to exhaust, and the valve 33 will then immediately shift from the position shown in Fig. 1 to that shown in Fig. 2; this throwing of the valve being effected in part by the built-up compression pressure transmitted to the forward face of the flange 34 through the ports 49 and annular groove 48, and in part by the reduction in pressure to the rear of the valve occasioned by the connection of the space within the cylinder bore at the front side of the piston with exhaust. Obviously, depending upon the proportions of the parts, throw wholly by compression pressure, or in part by compression pressure and in part by reduction in pressure at the opposite (rearward) side of the valve, may be caused to take place. In any event, the valve will be shifted so promptly after uncovering of the groove 54 by the rearwardly moving piston commences, that no waste of pressure fluid will occur.

Forward movement of the motor piston upon its blow-striking stroke will be effected by fluid admitted through the passage 10, through the somewhat restricted annular opening 12, through the bore 31, through the counterbore 41, which provides a metering of the fluid for the forward working stroke of the piston, through the annular space 48, and the passages 49. A pressure differential exists in the spaces to the front and rear of the flange 36, due to the flow through the restricted passage 12, which tends to move the valve 33 to its forward position; but the valve is held in its rearward position by virtue of the larger pressure area at the forward side of the valve.

As the motor piston moves forward, its rear end will uncover the mouth of the port 52, and cylinder pressure will pass through the port 52, the passage 51, and the passage 50, to act upon the rear side of the flange 34 on the valve 33, and will cause the valve 33 to be moved forward to cut off the supply of motive fluid to the rear end of the cylinder, and assume its position for the rearward stroke, desirably shortly before the rear end of the piston reaches the rearward edge of the exhaust groove 54. The mode of operation of succeeding cycles will be understood from what has been so far said.

By virtue of the slight restriction of flow through the annular space 12, it will be observed that if the distributing valve should happen to be in the position of Fig. 2, and the piston in the forward end of the cylinder with the rear end of the cylinder open to exhaust, when the throttle

valve is opened, the valve 33, due to the large differential in pressure which would exist between the spaces in front of and to the rear of the flange 36, will be promptly moved to the position of Fig. 1, and set the motor in operation. The vent port 53 also plays the additional function of preventing the building up of leakage pressures which might interfere with the starting of the motor.

It will be noted that in the preferred embodiment described and illustrated, the distributing valve is shifted, upon the forward movement of the motor piston, by piston controlled pressure, and upon the rearward pass of the motor piston, by a combination of the building up of a compression pressure and the relieving of an opposing pressure as the exhaust port is reached and uncovered by the rearwardly moving piston.

As a result of this invention, it will be noted that an improved pressure fluid motor is provided, having a novel and improved fluid distribution means, whereby certainty of starting is assured, whereby power may be increased, and whereby air consumption may be maintained at a minimum with respect to the power delivered. These and other uses and advantages of the improved pressure fluid motor will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a pressure fluid motor, in combination, a cylinder having a bore, a piston reciprocable in said bore, and fluid distribution means for supplying pressure fluid to and exhausting fluid from said cylinder bore for effecting reciprocation of said piston comprising means providing a valve chamber having valve seat surfaces at its opposite ends, a fluid distributing valve movably mounted in said valve chamber, and having seating surfaces at its remote extremities respectively adapted to seat against said valve seat surfaces, means cooperating with said valve providing a pair of internal pressure chambers separated by a restricted clearance space, and means forming fluid supply passages connecting the opposite ends of said valve chamber respectively to the opposite ends of said cylinder bore, said valve controlling the flow of pressure fluid from said internal pressure chambers through the opposite ends of said valve chamber past said valve seating surfaces to said supply passages.

2. In a pressure fluid motor, in combination, a cylinder having a bore, a piston reciprocable in said bore, and fluid distribution means for supplying pressure fluid to and exhausting fluid from said cylinder bore for effecting reciprocation of said piston comprising means providing a valve chamber having valve seat surfaces at its opposite ends, a fluid distributing valve movably mounted in said valve chamber and having valve seating surfaces at its remote extremities respectively adapted to seat against said valve seat surfaces, said valve having an annular flange projecting inwardly therein and arranged between said valve seating surfaces, means cooperating with said valve flange providing a pair of internal pressure chambers, said valve flange separating said chambers and providing a restricted

- clearance space therebetween, the pressure fluid flowing from one pressure chamber to the other through said clearance space, and means forming fluid supply passages connecting the opposite ends 5 of said valve chamber respectively to the opposite ends of the cylinder bore, said valve controlling the flow of pressure fluid from said internal pressure chambers through the opposite ends of the valve chamber past said valve seating surfaces to said supply passages.
3. In a pressure fluid motor, in combination, a cylinder having a bore, a piston reciprocable in said bore, and fluid distribution means for supplying pressure fluid to and exhausting fluid from 10 said cylinder bore for effecting reciprocation of said piston comprising means providing a valve chamber having valve seat surfaces at its opposite ends, said valve chamber having an enlarged bore and a reduced bore, a fluid distributing valve 15 reciprocably mounted in said valve chamber and having an external flange slidably fitting said enlarged bore and a sleeve-like body portion slidably fitting said reduced bore, said sleeve-like body portion having valve seating surfaces at the 20 remote extremities thereof respectively adapted to seat against said valve seat surfaces, and means providing fluid supply passages leading from the opposite ends of said valve chamber respectively to the opposite ends of said cylinder bore, said 25 valve controlling the flow of pressure fluid through the opposite ends of said valve chamber past said valve seating surfaces to said supply passages.
4. In a pressure fluid motor, in combination, a cylinder having a bore, a piston reciprocable in said bore, and fluid distribution means for supplying pressure fluid to and exhausting fluid from 30 said cylinder bore for effecting reciprocation of said piston comprising means providing a valve chamber having valve seat surfaces at its opposite ends, said valve chamber having enlarged end bores and a reduced intermediate bore, means providing fluid supply passages for connecting said enlarged bores respectively with the opposite 35 ends of said cylinder bore, and a fluid distributing valve reciprocably mounted in said valve chamber and having an external flange slidably fitting one enlarged bore and a sleeve-like body portion slidably fitting said reduced bore and projecting within said other enlarged bore, said sleeve-like body portion having valve seating surfaces at its remote extremities respectively adapted to seat against said valve seat surfaces, said valve controlling the flow of pressure fluid 40 through the opposite ends of said valve chamber past said valve seating surfaces to said supply passages.
5. In a pressure fluid motor, in combination, a cylinder having a bore, a piston reciprocable in said bore, and fluid distribution means for supplying pressure fluid to and exhausting fluid from 45 said cylinder bore for effecting reciprocation of said piston comprising means providing a valve chamber having valve seat surfaces at its opposite ends, said valve chamber having enlarged and reduced bores, a fluid distributing valve reciprocably mounted in said valve chamber and having an external flange slidably fitting the enlarged bore and a sleeve-like body portion slidably fitting the reduced bore, said sleeve-like body portion having valve seating surfaces at its remote extremities respectively adapted to seat against 50 said valve seat surfaces and said valve having an internal flange projecting inwardly therein and spaced inwardly of said valve seating surfaces,

means cooperating with said valve providing a pair of internal pressure chambers within the valve, said internal valve flange separating said chambers and providing a restricted clearance space therebetween, the pressure fluid flowing 5 from one pressure chamber to the other through said clearance space, and means providing fluid supply passages connecting the opposite ends of the valve chamber respectively with the opposite ends of the cylinder bore, said valve controlling 10 the flow of pressure fluid from said internal pressure chambers through the opposite ends of said valve chamber past said valve seating surfaces to said supply passages.

6. In a pressure fluid motor, in combination, a cylinder having a bore, a piston reciprocable in said bore, and fluid distribution means for supplying pressure fluid to and exhausting fluid from said cylinder bore for effecting reciprocation of said piston comprising means providing a valve 15 chamber having valve seat surfaces at its opposite ends, a fluid distributing valve reciprocably mounted in said valve chamber and having valve seating surfaces at its remote extremities respectively adapted to seat against said valve seat 20 surfaces, means cooperating with said valve inwardly of said valve seating surfaces providing metering spaces through which fluid must flow to the opposite ends of said valve chamber, and means providing fluid supply passages for connecting the opposite ends of said valve chamber respectively to the opposite ends of said cylinder bore, said valve controlling the flow of fluid 25 through said metering spaces and past said valve seating surfaces through the opposite ends of said 30 valve chamber to said supply passages.

7. In a pressure fluid motor, in combination, a cylinder having a bore, a piston reciprocable in said bore, and fluid distribution means for supplying pressure fluid to and exhausting fluid from 35 said cylinder bore for effecting reciprocation of said piston comprising means providing a valve chamber having valve seat surfaces at its opposite ends, a fluid distributing valve reciprocably mounted in said valve chamber and slidably 40 guided in said chamber solely at its exterior periphery, said valve having valve seating surfaces at its remote extremities respectively adapted to seat against said valve seat surfaces and provided with internal bores within its opposite ends inwardly of said valve seating surfaces, means at 45 the opposite ends of the valve chamber providing a sliding fit with said valve bores respectively, said valve bores, as the valve reciprocates, moving alternately into sliding engagement with said 50 sliding-fit-providing means, and means forming fluid supply passages connecting the opposite ends of said valve chamber respectively to the opposite ends of said cylinder bore, said supply 55 passages having fluid flow to them controlled by said valve and fluid flowing through said supply passages flowing past said sliding-fit-providing means and said valve seating surfaces in the different seated positions of said valve.

8. In a pressure fluid motor, in combination, a cylinder having a bore, a piston reciprocable in said bore, and fluid distribution means for supplying pressure fluid to and exhausting fluid from said cylinder bore for effecting reciprocation of said piston comprising means providing a valve 60 chamber having valve seat surfaces at its opposite ends, a fluid distributing valve reciprocably mounted in said valve chamber and slidably guided in said chamber solely at its exterior periphery, said valve having valve seating surfaces 65

at its remote extremities respectively adapted to seat against said valve seat surfaces and provided with internal bores within its opposite ends inwardly of said valve seating surfaces, means at 5 the opposite ends of the valve chamber providing a sliding fit with said valve bores respectively, said valve bores, as the valve reciprocates, moving alternately into sliding engagement with said sliding-fit-providing means, means forming fluid 10 supply passages connecting the opposite ends of said valve chamber respectively to the opposite ends of said cylinder bore, said supply passages having fluid flow to them controlled by said valve and fluid flowing through said supply passages 15 flowing past said sliding-fit-providing means and said valve seating surfaces in the different seated positions of said valve, and means cooperating with said sliding-fit-providing means for metering the fluid flowing past said valve seating 20 surfaces at the opposite ends of said valve.

9. In a pressure fluid motor, in combination, a cylinder having a bore, a piston reciprocable in said bore, and fluid distribution means for supplying pressure fluid to and exhausting fluid from 25 said cylinder bore for effecting reciprocation of said piston comprising means providing a valve chamber having valve seat surfaces at its opposite ends, a fluid distributing valve reciprocably mounted in said valve chamber and slidably 30 guided therein solely at its exterior periphery, said valve having end seating surfaces at its remote extremities and provided with internal bores within its opposite ends inwardly of said end seating surfaces, means at the opposite ends of 35 the valve chamber providing a sliding fit with said valve bores, said valve bores, as the valve reciprocates, moving alternately into sliding engagement with said sliding-fit-providing means, means cooperating with said valve bores and said 40 sliding-fit-providing means providing an internal pressure fluid supply within the valve, and means forming fluid supply passages connecting the opposite ends of said valve chamber respectively with the opposite ends of said cylinder bore, said 45 valve controlling the flow of pressure fluid from said internal pressure fluid supply past said sliding-fit-providing means and the seating surfaces at the opposite ends of the valve to said supply passages.

10. In combination, in a pressure fluid motor, a cylinder, a piston therein, and fluid distribution means for said motor including passage means for supplying operating fluid respectively to the opposite ends of said piston, an operating fluid supply, and valve means for controlling the communication of said passage means with said fluid supply, said valve means having end seating surfaces at the remote extremities thereof, and means cooperating with said valve means inwardly of said end seating surfaces thereof providing metered flow of operating fluid to the opposite ends of said cylinder, said valve means so formed and so arranged with respect to said cooperating metering-providing means as to preclude simultaneous communication of both of said passage means with said fluid supply. 10 15

11. In a pressure fluid motor, in combination, a cylinder having a bore, a piston reciprocable in said bore, and fluid distribution means for supplying pressure fluid to and exhausting fluid from 20 said cylinder bore for effecting reciprocation of said piston comprising means providing a valve chamber having valve seat surfaces at its opposite ends, a fluid distributing valve reciprocably 25 mounted in said valve chamber and having valve seating surfaces at its remote extremities respectively adapted to seat against said valve seat surfaces, means cooperating with the opposite ends of said valve inwardly of said valve seating surfaces providing metering spaces through which fluid must flow to the opposite ends of said valve chamber, and means providing fluid supply passages for conducting pressure fluid from the opposite ends of said valve chamber respectively to 30 the opposite ends of said cylinder bore, said valve controlling the flow of pressure fluid through said metering spaces past said valve seating surfaces to the opposite ends of said valve chamber, and said metering spaces and the opposite ends of 35 the valve being so spaced that when the valve is in its central position during movement of the valve between its opposite seated positions, flow of pressure fluid through both metering spaces is 40 momentarily completely cut off. 45

JOHN CLARK CURTIS.
